UNITED STATES PATENT OFFICE.

DAVID T. OWEN, OF CLEVELAND, OHIO.

COMBINED BED AND COUCH.

SPECIFICATION forming part of Letters Patent No. 730,392, dated June 9, 1903.

Application filed March 20, 1902. Serial No. 99,076. (No model.)

To all whom it may concern:

Be it known that I, DAVID T. OWEN, a citizen of the United States, residing at Cleveland, in the county of Cuyahoga and State of Ohio, have invented certain new and useful Improvements in a Combined Bed and Couch; and I do declare that the following is a full, clear, and exact description of the invention, which will enable others skilled in the art to which it appertains to make and use the same.

My invention relates to a combined bed and couch; and the invention consists in a bed and couch and intervening mechanism for raising and lowering the couch automatically when the bed is raised and lowered, all substantially as shown and described, and particularly pointed out in the claims.

In the accompanying drawings, Figure 1 is a perspective view of my invention, in which the bed is folded and the couch is raised. Fig. 2 is a plan view of the said parts on a line corresponding to *x x*; Fig. 3, the bed and cabinet being in cross-section. Fig. 3 is a vertical end elevation of the bed and couch shown in Figs. 1 and 2 on a line corresponding to *y y*, Fig. 2. Fig. 4 is an end elevation on the same line as Fig. 3, showing the couch down and the bed over it in position to be occupied. Fig. 5 is an enlarged inside perspective view of the mechanism for raising and lowering the couch as it is shown in the foregoing views. Fig. 6 is an end elevation of a section of bed and couch and a modified form of automatic mechanism connecting said parts.

In a combined bed and couch of the character thus shown, wherein the couch is to be used as couches ordinarily are when the bed is folded or raised and out of the way, it is desirable that the couch be so arranged and supported that it can be raised and lowered according as it is to be in or out of use. If it be not capable of movement in this way and is used with a bed foldable over it, the couch will be either too low for comfort as a seat, or if permanently high enough for a seat it will be so high that the bed necessarily will have to be raised above what is desirable in order to fold over it for use, and it is neither convenient nor really practicable to make a heavy couch adjustable up and down by hand, so as to adapt it to use both as a couch-seat and

a bed at the usual level. I have conceived the idea of a mechanical connection and operation between the bed and couch that will raise the couch automatically when the bed is raised and lower the couch when the bed is lowered. By these means the couch will be automatically raised to a comfortable seating elevation and held in that position by its controlling mechanism when the bed is up, while it will be also automatically lowered when the bed is turned down for use, as seen in Fig. 4. This assures a comfortable position for both bed and couch and controls the position of the couch by simply raising and lowering the bed and without material addition of labor in effecting the movements of the bed itself.

To these several ends the invention comprises, first, a combined bed and couch frame A, referred to hereinafter as the "main" frame, which is preferably of an attractive cabinet form and also preferably equipped at its top with a book-shelf *a'*, and when finished and furnished—for example, as seen in Fig. 1—it becomes an attractive article of furniture with practically no suggestion that it is a folding bed. This diversion from the real character of the article is purposely carried out in all the furnishings of the bed, and hence the bottom of the mattress or mattress-frame B is attractively upholstered, as seen at *b*, in keeping with the upholstering upon the couch C, and this gives the bottom *b* the appearance of a handsome and expensive elevated back for the couch itself, while the books and curtains above further divert the mind from the idea of its being a bed. This makes the article desirable and popular for furnishing apartment and other rooms where the suite is limited or where circumstances demand that the family should occupy small apartments and possibly use the sitting-room also as a bedroom. The principle of construction is the same in all cases, and the mattress and mattress-frame are adapted to be folded in an upright position with their edges within the ends of main frame A when raised. The said frame has its pivots at *a*, with its lower portion projecting behind and beneath said pivots, as seen in Figs. 3 and 4. This rearward and downward projecting portion is utilized, as seen in these figures, as a means of engagement for the

couch-operating mechanism. The said mechanism comprises, first, a set of standards 2 upon the base at each end of the couch-frame, and upon these are supported double-armed levers L, having opposite arms 3 and 4 of equal length, and arms 3 are pivotally connected to the bottom of the couch C, while the arms 4 are connected by a controlling bar or rod 5, and a link 6 is attached at one end 10 to the nearest arm 4 and at the other end to the lower portion of the bed-frame below its pivot α . A similar construction and arrangement of mechanism is provided at each end of the couch and bed, and the levers and their 15 arms are of such length and are so constructed and arranged in respect to all the parts that they give the desired up-and-down and forward-and-back movement to the couch when the bed is raised and lowered. The effect of this arrangement further is to carry the couch forward away from the bed when down, as in Fig. 4, so that the extremities of the levers 3 and 4 travel practically on an arc of a circle in each movement, with the highest 25 point of travel where the couch rests in the raised portion. This takes the couch away from the bed sufficiently to enable the bed to turn down on its pivot α , and in so far as the operation is concerned the folding down 30 of the bed is practically as easy and simple as if there were no couch connected with it. When the bed is raised or folded in the cabinet, the movements are directly the reverse of the foregoing, and the couch is restored to 35 its raised position for use, as seen in Figs. 1 and 3.

The construction and arrangement of parts just described is likewise clear in Fig. 5, wherein said parts are enlarged to show their 40 construction more plainly than would otherwise appear.

A modification of the mechanism above described for automatically controlling the position of the couch through the bed is seen 45 in Fig. 6, wherein the couch stands on two posts or supports 7 at each end and pivotally engaged with the couch-frame at one end and with the base of main frame A at the other end, and a link 8 connects the end of the 50 couch with bed-frame B some distance above pivot α . The effect obtained by this construction and arrangement of parts is identically the same as by the construction in Figs. 1 to 4, and so it occurs when the bed is lowered for use that link 8 serves to carry the 55 couch C forward and downward horizontally and on curved lines, as occurs in Figs. 3 and 4, and in like manner the couch is raised and held in raised position through the folding of 60 the bed into the cabinet.

I might of course suggest still other modifications or forms of construction and connection between the bed and couch frames for automatically controlling the positions of 65 the couch through the bed more or less after the manner of the forms herein shown; but I do not deem it necessary to elaborate this

portion of the invention at this time, because, so far as I know and believe, the idea of the automatic operation herein set forth of 70 the couch through the movements of the bed is broadly new.

What I claim is—

1. In a combined bed and couch, a movable couch, a bed pivoted at the rear side of the 75 couch and mechanism connecting the couch and bed and constructed to bring the bed into vertical position behind the couch to form a back thereto and to lower the couch automatically when the bed is lowered, substantially as described.

2. In a combined bed and couch, a seat-support and a movable seat thereon, in combination with a bed pivotally supported at the rear side of the seat and adapted to fold over 85 the same and having its bottom finished to form a back to the seat, and mechanism connecting the seat with the bed and constructed to raise the seat when the bed is raised, substantially as described.

3. In a combined bed and couch, a main frame, a movable couch therein and a folding bed supported on a fixed pivot on the said frame at the rear side of the couch and having its bottom finished to form a finished back 95 for the couch, and mechanism to raise and lower the couch when the bed is raised and lowered, the said mechanism being pivotally connected to both couch and bed, substantially as described.

4. A couch and a folding bed supported in an upright position at the rear side of the couch and forming a back therefor and adapted to turn on its pivots over the couch and constitute a bed, and mechanism connecting 105 the ends of the couch with the bed, said mechanism constructed to automatically raise and lower the couch on an arc of a circle when the bed is raised and lowered, whereby the couch is carried bodily away from the bed 110 when the bed is lowered, substantially as described.

5. In folding beds, a main frame, a bed-frame having fixed pivots thereon at its ends on which it is adapted to be raised and lowered, a movable couch-seat in front of said bed-frame and pivoted supports for the said couch-seat having fixed pivots beneath said seat and link connections between the ends of the bed-frame and the said supports for 120 the couch-seat, whereby the said seat is raised and lowered automatically when the bed is raised and lowered, and the bed-frame having a finished bottom constituting a back for the couch, substantially as described.

6. In a combined folding bed and movable couch, a bed on fixed pivots and a couch in front of the bed and supports for the couch constructed and arranged to travel on the arc of a circle and carry the couch horizontally 130 forward and downward away from the bed, and links operatively connecting the said parts with the ends of the bed, substantially as described.

7. The main frame, a couch and pivot-supports for the couch on the said frame, in combination with a folding bed at the rear of the couch having fixed pivots on a plane below the top of the couch when the same is raised, and a finished bottom forming the back of the couch, and mechanism pivotally connecting the couch with the bed and constructed to move the couch to and from the pivots of the bed when the bed is raised and lowered, to substantially as described.
- Witness my hand to the foregoing specification this 28th day of February, 1902.
- DAVID T. OWEN.
